UNITED STATES PATENT OFFICE.

WILLIAM N. GREER, OF WATERTOWN, SOUTH DAKOTA, ASSIGNOR OF ONE-HALF TO P. J. COOK, OF GREELEY, NEBRASKA.

COMPOUND TOOL.

SPECIFICATION forming part of Letters Patent No. 634,336, dated October 3, 1899.

Application filed June 10, 1897. Renewed August 17, 1899. Serial No. 727,539. (No model.)

To all whom it may concern:

Be it known that I, WILLIAM N. GREER, a citizen of the United States, residing at Watertown, in the county of Codington and State of 5 South Dakota, have invented certain new and useful Improvements in Compound Tools; and I do hereby declare the following to be a full, clear, and exact description of the invention, such as will enable others skilled in the 10 art to which it appertains to make and use the same.

My invention has relation to improvements in compound tools, and particularly to that class which may be conveniently carried in 15 the pocket; and the object is to provide a simple, convenient, and useful device of this nature.

To this end the novelty consists in the construction, combination, and arrangement of 20 the several parts of the same, as will be hereinafter more fully described, and particularly pointed out in the claims.

In the accompanying drawings the same reference characters indicate the same parts 25 of the invention.

Figure 1 is a perspective view of my improved compound tool open. Fig. 2 is a similar view of the tool closed.

My invention embodies in one compact implement a screw-driver, corkscrew, spoke-wrench, a hook for cleaning horses' hoofs, a tool for perforating leather, a penknife, glass-cutter, and a tack or nailclaw.

1 represents an approximately rectangular 30 slotted shank shaped at one end to form the screw-driver 2 and provided at its opposite end with the integral right-angular lugs 3.

4 and 5 are oppositely-disposed hook-shaped members integral with the free ends of the 35 parallel arms 6, and the opposite ends of said arms are pivoted on the outer faces of the lugs 3 by the transverse rivets 7 and together when opened back to back, form a convenient and powerful handle for the screw-driver 45 and when closed are a casing for the entire combination, the inner face of the member 4 closing frictionally tight against the outer face of the member 5, the recess 8 being provided to receive the claw ends and prevent 50 same from abrading the pocket.

The member 5 constitutes a bill-shaped

hook which is very convenient for cleaning horses' hoofs and other purposes. The heel of said hook is provided with the longitudinal slot 9, in which is journaled an edged wheel 55 10 on the transverse rivet 12, the said wheel being an effective glass-cutter. The oppositely-disposed hook 4 is bifurcated to form a tack and nail claw, and between the integral parallel arms 6 of this member is pivoted 60 the member 13 on the transverse rivet 14, the said member constituting an integral corkscrew and bicycle spoke-wrench, and when either tool is in use it is held at a right angle to the arms 6 in the transverse grooves 65 15 on the inner faces of said arms.

16 represents integral lugs on the inner face of the arms 6, and said lugs are adapted to limit the outward movement of said arms and to hold them firmly in operative position. 70

Between the lugs 3 and on opposite sides of the shank 1 are pivoted the knife-blade 17 and the punch 18, the said blade sheathing in the slotted shank 1 and in the arms of the member 4. 75

The punch 18 is crescent-shaped in cross-section at the heel and tapers to a sharp point, its edges being sharpened so that a half-turn to the right or left after it is inserted in leather or similar material will result in a 80 clean-cut circular orifice.

A V-shaped spring 19 of the construction commonly used in pocket-knives (shown in dotted lines, Fig. 2) is employed to secure the blade and punch in an open or closed position, and the said spring is secured in the slotted shank 1 by the rivets 20. 85

It will be noticed that the slotted shank 1 is rounded at 21 to conform to the groove in the punch, so that when the said punch is 90 clasped shut it fits snugly thereon, and its cutting edges are thus effectually protected.

Having thus fully described my invention, what I claim as new and useful, and desire to secure by Letters Patent of the United States, 95 is—

1. A compound tool, comprising a slotted shank 1 having a convex face 21, a concavo-convex punch pivoted in said shank, the concave face of said punch adapted to close down 100 upon the convex face of said shank, a bifurcated hook 4 having integral parallel arms 6,

the free ends of said arms pivoted to said shank and adapted to close down over said punch, substantially as shown and described.

2. A compound tool, comprising a slotted shank 1 having a convex face 21, a concavo-convex punch pivoted in said shank, the concave face of said punch adapted to close down upon the convex face of said shank, a bifurcated hook 4 having integral parallel arms 6, the free ends of said arms pivoted to said shank and adapted to close down over said punch, a hook member 5 pivoted to said slotted shank by means of integral parallel arms, the inner face of the member 4 adapted to close frictionally tight upon the outer face of the member 5, substantially as described and set forth.

3. A compound tool, comprising the slotted shank 1, the integral screw-driver 2 on one end thereof, and on the opposite end the in-

tegral right-angular lugs 3, a hook 5 for cleaning horses' hoofs, an edged wheel for cutting glass journaled in the heel of said hook, a second oppositely-disposed hook 4, bifurcated to adapt it for use as a tack-claw, both hooks 25 having integral parallel arms 6, the free ends of which are pivoted to the outer faces of the lugs 3, an integral cork-screw and spoke-wrench pivoted between the arms of said hook 4 and held in operative position by the transverse grooves 15, integral lugs 16 on the inner faces of said arms near the pivotal ends thereof and adapted to limit their outward movement, substantially as shown and described.

In testimony whereof I affix my signature 35 in presence of two witnesses.

WILLIAM N. GREER.
